ELECTROMAGNETIC PICK-UP TOOL

Filed June 6, 1930

UNITED STATES PATENT OFFICE

DEANE H. WEBB, OF BEND, OREGON

ELECTROMAGNETIC PICK-UP TOOL

Application filed June 6, 1930. Serial No. 459,552.

My invention relates to an electromagnetic pick-up tool.

In accordance with my invention, I provide an electromagnetic pick-up tool or implement, which may be conveniently manipulated for removing iron elements from inaccessible places.

The tool preferably embodies an electromagnet constituting a unit, and so wound as to be small and strong in its electromagnetic force. The electromagnet is enclosed in a preferably non-magnetic case to be protected thereby from oil, grease, water, or mild chemicals, which might tend to destroy the insulation of the winding. The handle of the device is preferably in the form of a tube, having a relatively small diameter, whereby the tube may be bent at different angles to enable the tool to be inserted into inaccessible places. The tube carries the case and is adapted to receive a lead wire connected with one end of the electromagnetic winding, the other end of the winding being connected with the case. The forward end of the case is formed open and this permits of the insertion of the lead wire, and the electromagnet into the tube and case, respectively in one operation. The end of the case is closed by a head, preferably forming a part of the core of the electromagnet. The co-acting lead wire is attached to the tubular handle and a flexible sleeve is preferably secured to the rear end of the tubular handle for protecting the lead wires. The tool is extremely simple in construction, strong, durable, and convenient in use.

Other objects and advantages of the invention, will be apparent during the course of the following description.

In the accompanying drawings, forming a part of this specification, and in which like numerals are employed to designate like parts throughout the same,

Figure 1 is a central vertical longitudinal section through the tool embodying my invention,

Figure 2 is a transverse section taken on line 2-2 of Figure 1,

Figure 3 is a side elevation of the tool,

showing the tubular handle angularly bent or adjusted.

In the drawings, wherein for the purpose of illustration, is shown a preferred embodiment of my invention, the numeral 5 designates a preferably cylindrical case, having its forward end open and its rear end connected with a tapered head 6, decreasing in diameter rearwardly and carrying a tubular handle 7, these parts being preferably formed integral, and preferably formed of copper or some other pliable non-magnetic material. The tubular handle 7 has a relatively small diameter, as shown.

The device embodies an electromagnet inserted within the case 5, and this electromagnet includes a spool-core 8, formed of iron or the like, embodying end discs 9 and 10. The disc 9 is of a diameter to have a sliding fit within the case 5, while the disc 10 has a diameter substantially the same as the exterior diameter of the case. The core 8 has a winding 11 thereon, formed of insulated wire, as is well known. One end of the winding is electrically connected with the case 5, as shown at 12. The disc 10 may be rigidly attached to the case 5 by any suitable means, preferably by soldering at 13, for producing a gas-tight joint.

The tubular handle 7 is of small diameter, and has a bore of small diameter for receiving an insulated lead wire 13, preferably having a close sliding fit therein to close the bore. This lead wire has electrical connection with the opposite end of the winding 11, adjacent to the disc 9. The lead wire 13 extends rearwardly beyond the tubular handle 7 and is equipped with a resilient clip 14, or the like. The other insulated lead wire 15 may have a resilient clip 16, and the lead wire 15 is attached to the rear end of the tubular handle 7.

The numeral 17 designates a flexible protecting sleeve, preferably formed of a wire coil, which is attached to the rear end of the tubular handle 7 and receives the wires 13 and 15 therethrough, preventing the insulation of the same being injured.

In the use of the device, the handle 7 by virtue of its small diameter may be angular.

ly adjusted or bent so that the case 5 may be inserted into inaccessible places, while the handle 7 is sufficiently stiff to serve as a support for the case. The handle 7 is, therefore, readily bendable. The wire 13 closes the bore of the tubular handle, thereby sealing the rear end of the case. The two lead wires 13 and 15 may be connected with the opposite poles of the source of current, and when this is done, the electromagnet is energized and the metal base will be attracted to the electromagnet and held thereby until removed to the desired place.

It is to be understood that the form of my invention, herewith shown and described, is to be taken as a preferred example of the same, and that various changes in the shape, size, and arrangement of parts may be resorted to, without departing from the spirit 20 of my invention, or the scope of the subjoined claims.

Having thus described my invention, I claim:—

1. An electro-magnetic pick-up tool comprising a case having its forward end open and its rear end provided with a head covering the same, a tubular handle carried by the head, an electro-magnet insertable as a unit into the casing through its forward open end, said electro-magnet embodying a spool core having forward and rear discs, the rear disc being of a size for insertion within the case, and the forward disc serving to close the forward open end of the case and having a fluid-tight joint therewith, a winding carried by the spool core, and a lead wire extending through the tubular handle and connected with the winding.

2. An electro-magnetic pick-up tool comprising a case having its forward end open and its rear end provided with a head covering the same, a tubular handle having a relatively small diameter attached to the head and being bendable, an electro-magnet insertable as a unit through the forward open end of the case, said electro-magnet embodying a spool core having forward and rear discs, the rear disc having a diameter to permit of its insertion within the case, and the forward disc having a diameter larger than the bore of the case and engaging the forward end of the case to close the same, and having a fluid-tight joint with such forward end, a winding carried by the spool core, and a wire extending through the tubular handle and having a snug fit therein for closing the bore of the tubular handle and connected with said winding.

In testimony whereof I affix my signature.

DEANE H. WEBB.
